UNITED STATES PATENT OFFICE

2,503,962

TOILET

Melvin F. Moen, Waukesha, Wis.

Application March 4, 1948, Serial No. 13,007

2 Claims. (Cl. 4—10)

1

The invention relates to toilets and more particularly to toilets for summer cottages or for cottages in climates in which the temperatures do not go below freezing.

The general object of the invention is to provide a toilet which may be installed adjacent to or in a wing of a cottage of the type above described and will be sanitary and free from objectionable odors. More particularly, the toilet includes a tilttable bowl, means for flushing the bowl, and an exteriorly vented pit or waste storage space disposed outside of the cottage or building housing the toilet and into which the bowl discharges, said pit having a removable top cover.

A further object of the invention is to provide a toilet of the character above described having a tilttable bowl with means for mounting said bowl in the seat support so that it may be readily removed therefrom for cleaning if necessary.

A further object of the invention is to provide a toilet of the character above described having a tilttable bowl discharging into a storage space, which bowl acts as a closure between said space and the seat housing of the toilet.

The invention further consists in the several features hereinafter set forth and more particularly defined by claims at the conclusion hereof.

In the drawings:

Fig. 1 is a vertical sectional view through a toilet embodying the invention;

Fig. 2 is a vertical sectional view taken on the line 2—2 of Fig. 1;

Fig. 3 is a horizontal sectional view taken on the line 3—3 of Fig. 1, parts being broken away;

Fig. 4 is a detailed perspective view of the pivot structure for the bowl, parts being broken away and parts being shown in section.

Referring to the drawings, the numeral 5 designates an enclosing structure, such as an out-house or a wing of a dwelling, provided with an entrance 6 and a floor 7, and 8 designates a wood line pit whose top opening 9 is normally covered by a slab 10 of concrete provided with a vent pipe 11 but which cover may be moved to one side of the opening 9, if desired. The pit 8 is disposed outside of structure 5 and is connected with an opening 12 in the floor 7 by an upper lateral extension or passage 13.

A toilet seat housing or support 15 of sheet metal having a hinged top cover 16, upon which is mounted a toilet seat 17 provided with a cover 18 hinged thereto at 19, has side walls 20 which at their lower ends project down into the opening 12 and which carry an angled metal member 21 adapted to engage the floor 7 about the opening 12 except for that portion bounded by the

wall 22 of the structure 5 to mount the support upon the floor.

5 A water storage receptacle 23 is mounted on a shelf 24 on the outside of the structure 5 and has a discharge pipe 25 leading from the bottom thereof, through a wall of the structure 5 and into the upper portion of the support 15 in which it discharges, the discharge being controlled by a manually operated push type valve 26 disposed adjacent the seat 17. This pipe 25 may have a depending extension 27 connected to it by an elbow fitting 28 and which extension may be swung toward the wall 22 in case it is necessary to remove the bowl hereinafter described.

10 15 A bowl 29 of sheet metal and of scoop-like form is provided with oppositely disposed trunnions 30 which are fulcrumed in bearings provided in opposite sides of the support 15. Preferably each bearing is formed by a half bearing 31 fixed to the support at the end of a vertically extending slot 32 therein and a half bearing 33 on a plate 34 slidably mounted on flanges 40 at the sides of the slot 32 so that when the cover 16 is tipped up to the dotted line position shown 15 in Fig. 1, the plates 34 may be removed, and the bowl 29 may then be turned at right angles to the position shown in Fig. 1 and then lifted upwardly out of said housing, the extension 27, if used, having been turned toward the wall 22 as 20 previously described to prevent interference with the bowl. One of the trunnions 30 extends beyond the wall of the support 15 and has a lever arm 35 secured thereto provided with a manually operable handle 36 disposed adjacent the toilet 25 seat 17 which may be swung upwardly to tip the bowl 29 to a position in which its contents are discharged into the pit 8.

It is to be noted that when the bowl 29 is in the position shown in Fig. 1, the forward end 40 37 of its discharge end 38 is engaged with the lower edge 39 of the wall of the support 15 adjacent the pit, and it is normally held in this position due to the greater weight of the main 45 body portion of the bowl acting on the opposite side, that is, the center of gravity of the bowl is offset to the right of it pivots. The bowl preferably has a close fit with the sides of the housing 15, so that it acts as a closure for the lower part thereof, and therefore, blocks the passage of any objectionable odors which, however, are free to escape from the exteriorly disposed vent pipe 11. Also the discharge of water from the receptacle 23 into the bowl serves to thoroughly flush and clean the same. The re- 50

ceptacle 23 may be charged with fresh water, or it may be arranged to receive rain water.

I desire it to be understood that this invention is not to be limited to any particular form or arrangement of parts except in so far as such limitations are included in the claims.

What I claim as my invention is:

1. In a toilet of the type described, the combination with an enclosing structure for the toilet, of an exteriorly vented storage space disposed outside of and below said structure and connected at one side of its upper end to an opening in the floor of said structure, a toilet seat, a support for said seat mounted over said opening, a bowl tiltably mounted on said support partly projecting into said space and adapted to discharge directly into said space.

2. A structure as claimed in claim 1 in which

the bowl has its discharge end projecting into the upper end of said storage space and forming a stop for maintaining the bowl in an operative position.

MELVIN F. MOEN.
